UNITED STATES PATENT OFFICE.

HENRY C. EGERTON, OF RIDGEWOOD, NEW JERSEY.

PARTIALLY-STIFFENED SHOE-SOLE.

1,352,737.

Specification of Letters Patent. Patented Sept. 14, 1920.

Application filed December 24, 1918. Serial No. 268,157.

To all whom it may concern:

Be it known that I, HENRY C. EGERTON, a citizen of the United States, and resident of Ridgewood, county of Bergen, State of New Jersey, have made a certain new and useful Invention Relating to Partially-Stiffened Shoe-Soles, of which the following is a specification, taken in connection with the accompanying drawing, which forms a part of the same.

This invention relates especially to partially stiffened shoe soles of the general type covered by the Egerton Patent 1,282,399, of October 22, 1918, in which the stiffener members extend sufficiently under the front or body portion of the shoe sole to resiliently stiffen and protect the ball of the foot and other portions where the shoe sole engages the ground in ordinary walking, while the shank portion of the shoe sole is left in relatively unstiffened condition, so that it can readily retain such bent or curved shape as is necessary to fit the shank of the shoe beneath the instep. The stiffener members used for this purpose may comprise any desired suitable form of fabric or fibrous material, such as canvas, cotton or other cloth, fibrous sheets including paper pulp or the like, suitably coated or impregnated with phenolic condensation cementing stiffening material, in any desired way. A number of superimposed sheets of canvas impregnated with such dried phenolic condensation cementing material may be used to stiffen the front or body portion of the shoe sole and may be conveniently united thereto by a rubberized connector, such as a canvas or cloth layer previously frictioned or otherwise rubber coated on the side adjacent the composition sole which may be formed of any suitable rubber composition, and if desired be provided with any suitable form of heel. By having these special stiffener layers stop adjacent the shank portion of the shoe sole and preferably successively reduce their stiffness and strength as this point is approached so as to gradually lessen the stiffness and strength of this stiffening material, the shank and heel portion, if desired, may be left in substantially unstiffened condition when the rubber composition and other parts are vulcanized and cured together so that while the shoe sole may be conveniently molded and vulcanized in flat form it may be used

with any desired form of last so that the shank and heel may be arched or bent upward to the extent desired to support the instep of the foot.

In the accompanying drawing showing in 60 a somewhat diagrammatic way various illustrative embodiments of the invention.

Figure 1 is a top view of a shoe sole.

Fig. 2 is a corresponding sectional view in which the parts are shown in separated 65 position for greater clearness.

Fig. 3 is a corresponding section showing the finished shoe sole after these elements are united.

Fig. 4 is a longitudinal section through 70 another form of shoe sole; and

Figs. 5 and 6 are longitudinal sections showing still another construction.

The rubber shoe sole composition 1 may, if desired, be previously molded and profiled so that the thinner shank portion 2 and heel portion 3 where 1 is used may be joined by the beveled portion 20 with the thicker front or body portion of the shoe sole. If desired, the shoe sole around this 80 front body portion may be formed with a special stitching retainer member in the form of a heavy open mesh braid or fabric strip 12 which may be frictioned on one or both sides and molded into and preferably completed embedded in the rubber composition blank before it is vulcanized and the other parts united thereto. A plurality of suitable stiffener members or strips, such as 7, 8, 9, may be suitably united 90 in any desired way to the front or body portion of the shoe sole and as indicated in Figs. 1 and 2 the stiffener strips or members may have their rear edges 17, 18, 19, located adjacent the shank portion of the 95 shoe sole and preferably successively end on some such diagonal lines as indicated in Fig. 1 so as to be arranged in lapping position and progressively decrease the stiffness of the finished sole at this point and allow 100 the shank portion of the sole to bend with relatively little resistance. For some purposes it is also desirable to have the stiffener gradually decrease in strength toward the extreme front or toe portion and if desired 105 the stiffener members may have their front ends in generally similar stepped or lapping position so as to allow for the more ready bending of the toe which is desirable to minimize local wear in some cases. As in- 110

dicated some of these stiffener members or strips, such as 17, may be of relatively less lateral width also, so that as shown in Fig. 1 their edges 27 are farther inward than the 5 larger and longer strips having the edge portions 29 and it is of course understood that for some purposes a greater or less number of strips may be used to secure special stiffening action in some cases and 10 also that with specially heavy fabric or fibrous layers a single stiffening strip or member may be used for some purposes preferably after being coated or thoroughly impregnated with the phenolic condensation 15 cementing material to the desired extent.

A convenient and effective way to unite the stiffener members to the rubber composition forming the wearing surface of the sole is to interpose a fabric connector such 20 as the canvas or cloth strip 5 preferably having a frictioned or other rubber coating 6 thereon on the side with which the rubber sole engages while the other side of this connector may be coated with phenolic condensation cementing material, such as bakelite or condensite varnish, for instance. In some cases, however, the coated or impregnated stiffener members supply sufficient cementing material when the parts are heated and cured under pressure in a suitable mold so as to secure in position this connector layer which may sometimes extend more or less throughout the shank and heel portions of the sole as indicated in Figs. 2 30 and 3. It is sometimes desirable to have a rubberized facing member, such as 10, extending over part or all of the shoe sole and when as indicated this facing member has a frictioned or other rubber coating 6 on its exposed surface the completed shoe sole has a sufficient rubber coating on this side so that the ordinary rubber cements may be used therewith. If desired also in some cases an additional rubberized fabric 40 layer 11 may be used below the connector adjacent the shank and heel portions of the sole and this canvas or other fabric may advantageously be frictioned or rubberized on both surfaces to more securely unite it with 45 the coöperating elements. All of these parts may, of course, be assembled in a suitable mold and heated under pressure to the desired vulcanizing curing heats so that the 50 previously dried phenolic condensation cementing material is cured and the rubber sole composition simultaneously vulcanized and all the parts securely united together to form an integral shoe sole such as indicated in Fig. 3 in which the front or body portion 55 1 is stiffened to the desired extent and normally resiliently returns to its original flat form which is desirable for most purposes. At the same time the shank portion 2 may be readily bent or arched up to the extent 60 necessary to secure it to the insole and shoe 65

upper in resoling or in originally making the shoe and the sole shank is readily retained in this arched up position, especially where little or no fabric is united to this part of the sole, so that, if desired, the shoe 70 sole may be vulcanized and cured in the substantially flat condition indicated which also facilitates packing and shipping to some extent as well as making it unnecessary to have a number of different styles or shapes 75 of arched up shank portions as might be necessary if special stiffness or rigidity was given to this part of the sole.

In the form of sole shown in Fig. 4 the rubber or other composition wearing surface 1 may be tapered off at the point 20 20 into the much thinner shank portion 2 to which, if desired a heel portion 3 may be secured. The stiffener member is illustrated in this case as comprising two layers of 85 paper, fabric or other fibrous material, such, for instance, as two heavy canvas layers 7, 8, which are preferably thoroughly impregnated with phenolic condensation cementing material and dried before being assembled so that their rear edges 17, 18 at least are in overlapping position adjacent the shank portion of the sole. In this case also a suitable fabric connector layer, such as 26, may be used to facilitate the union of these 90 stiffener layers to the composition sole and where a rubber composition is used the frictioned or other rubberized coating 6 may advantageously be first applied to this connector on its under surface so that all the 100 parts may be cured, vulcanized and simultaneously united in the usual pressure mold employed. Thus the front or body portion of the one-piece rubber sole is strongly reinforced by this stiff and tough resilient material, so that it has about the same stiffness to bending and denting as high grade leather, while the thinner shank portion 2 has a much more yielding character and readily conforms to the stiffened shank of 110 the shoe to which it is attached especially since it is advantageous to have the rubber composition of a relatively pure high grade to secure improved wearing and non-slipping action.

Fig. 5 shows another form of shoe sole especially adapted for repair work in which no heel portion is provided, the rear edge or portion of this sole having its rubber element beveled off at 4 so that the one or more layers of fabric 21 which may be used are thus exposed and can be more readily united to the coöperating heel portions of the shoe. In this case two canvas or other fabric or fibrous stiffener layers 14, 15, are shown as 125 making up the stiffener member and the upper layer 15 may have its rear edge terminate at about the point 16 while its front portion may be located at about the point 25 so as to provide a relatively wider un- 130

stiffened edge portion which to a greater extent facilitates the trimming or shaping of the shoe sole so that a single size can be used for a greater range of work. The 5 other stiffener layer 14 may be, if desired, of relatively smaller area and these stiffener strips may be united to the rubber composition sole by a connector fabric layer or member 5 having the rubberized face 6 to 10 promote the vulcanizing union with the rubber composition below. If desired in this case also this connector may extend over the shank portion of the sole and in some cases also an additional rubberized fabric 15 layer 11 may be used in the shank and may have both its faces previously provided with a frictioned or other rubber coating to unite with the adjacent elements during the curing of the parts in the pressure molding operation. It is of course understood that the 20 relatively yielding shanks of any of these types of illustrative soles may be used with or secured to the shank portions of shoes which have been stiffened in any suitable 25 way to the extent desired. It is sometimes desirable to use a separate special arched up shank stiffener of fabric stiffened with such cured phenolic condensation cementing material and having a relatively thick and 30 strong central portion while the edges are preferably thinner or more penetrable to facilitate sewing or nailing between the shoe insole and the sole.

Fig. 6 shows this type of construction, 35 the rubber or other composition sole 1 having, if desired, a shank portion 2 and heel portion 3 and having a suitable stiffener element comprising fabric or other fibrous layers or strips 30, 31 carrying or impregnated with phenolic condensation cementing material. The connector 5 having, if desired, the rubberized lower surface 6 may be interposed between these stiffener members or strips and the rubber sole to facilitate 40 their union when the parts are heated under pressure to cure and solidify the cementing material used. For some purposes it is desirable to form alining or gripping means such as a recess in the sole to facilitate 45 connection or location of the separate shank or other stiffener with reference thereto. This may be conveniently done by curing the tip 31 of one or more of the stiffener layers in raised or separated position somewhat away from the other material 50 so as to form a gripping alining recess which may as indicated extend somewhat diagonally across the shoe sole. The shank stiffener may be formed of a plurality of 55 layers of canvas, paper or other fibrous material carrying and preferably thoroughly impregnated with such cured phenolic condensation cementing material so as to stiffen and strengthen the same and maintain its 60 desired arched up form. Three layers of 65

such stiffening fabric 38, 39, 40 are shown in this instance and the stiffener may as indicated have a reduced lower edge 36 adapted to coöperate with the gripping recess when the parts are assembled and stitched 70 or nailed to a shoe, the shank and heel portions of the sole being under these conditions bent up into the dotted position indicated. This reduced end 36 and also the lateral portions of this shank stiffener may, 75 if desired, be softer and more penetrable because containing less of the stiffening cementing material, if desired.

This invention has been described in connection with a number of illustrative embodiments, forms, proportions, elements, parts, shapes, materials, compositions, methods of preparation, production and use, to the details of which disclosure the invention is not of course to be limited, since what is 80 claimed as new and what is desired to be secured by Letters Patent is set forth in the appended claims:

1. The one-piece rubber shoe sole comprising a vulcanized rubber wearing surface and having its front body portion stiffened and strengthened by a fibrous stiffener member comprising a plurality of layers of fabric impregnated with cured phenolic condensation cementing material, 95 the rear edges of said fabric layers being arranged in diagonally lapping position adjacent the shank portion of the shoe sole to allow the ready yielding and flexure of said shank portion, a rubberized fabric 100 connector layer between said rubber tread portion and said stiffener member to more securely unite them and a rubberized facing member secured on the stiffened side of said shoe sole, said rubber tread portion being provided with an embedded fabric stitching retainer with which the attaching stitching is adapted to engage. 105

2. The one-piece rubber shoe sole comprising a vulcanized rubber wearing surface and having its front body portion stiffened and strengthened by a fibrous stiffener member comprising fabric impregnated with cured phenolic condensation cementing material, the rear edge of said fabric being arranged 110 in diagonal position adjacent the shank portion of the shoe sole to allow the ready yielding and flexure of said shank portion, and a rubberized fabric connector layer between said rubber tread portion and said stiffener 115 member to more securely unite them.

3. The one-piece rubber shoe sole comprising a vulcanized rubber composition wearing surface and having its front body portion stiffened and strengthened by a stiffener member comprising a plurality of layers of fabric carrying and impregnated with cured phenolic condensation cementing material, the rear edges of said fabric 125 layers being arranged in diagonally lapping 130

position adjacent the shank portion of the shoe sole to allow the ready yielding and flexure of said shank portion and a rubberized fabric connector layer between said rubber tread portion and said stiffener member.

5 4. The one-piece rubber shoe sole comprising a vulcanized rubber composition wearing surface and having its front body portion substantially flat and stiffened and 10 strengthened by a stiffener member comprising a plurality of layers of fabric carrying cured phenolic condensation cementing material, the rear edges of said fabric layers being arranged in lapping position adjacent 15 the shank portion of the shoe sole to allow the ready yielding of said shank portion, and a fabric connector layer between said rubber tread portion and said stiffener member to more securely unite them.

20 5. The one-piece rubber shoe sole comprising a vulcanized rubber composition wearing surface and having its front body portion stiffened and strengthened by a stiffener member comprising fabric carrying 25 cured phenolic condensation cementing material, the rear edge of said fabric being adjacent the shank portion of the shoe sole to allow the ready yielding of said shank portion and a fabric connector layer between 30 said rubber tread portion and said stiffener member to more securely unite them.

6. The one-piece shoe sole comprising a vulcanized rubber composition wearing surface having readily yielding shank portions 35 and having its front body stiffened and strengthened by a connected fibrous stiffener member comprising a plurality of layers of fabric carrying cured phenolic condensation cementing material, said fabric layers having rear portions formed adjacent the shank portion of the shoe sole with an external 40

alining recess for a coöperating stiffener member.

7. The shoe sole comprising a composition wearing surface and having its front body 45 portion stiffened and strengthened by a connected fibrous stiffener member comprising a plurality of layers of fabric carrying cured phenolic condensation cementing material, said fabric layers having rear portions arranged 50 in lapping position adjacent the shank portion of the shoe sole to make said shank portion relatively yielding.

8. The shoe sole comprising a composition wearing surface and having its front body 55 portion stiffened and strengthened by a connected fibrous stiffener member carrying cured phenolic condensation cementing material, having rear portions arranged adjacent the shank portion of the shoe sole to 60 make said shank portion relatively yielding.

9. The shoe sole comprising a vulcanized rubber composition wearing surface and having its front body portion stiffened and strengthened by a connected fibrous stiffener 65 member comprising fabric carrying cured phenolic condensation cementing material, said fabric having portions formed adjacent the shank portion of the shoe sole with an externally accessible alining recess for a coöperating stiffener member.

10. The shoe sole comprising a vulcanized rubber composition wearing surface and having its front body portion stiffened and strengthened by a connected fibrous stiffener member carrying cured phenolic condensation cementing material, said stiffener being formed with alining means for an externally applied coöperating stiffener member.

HENRY C. EGERTON.
